UNITED STATES PATENT OFFICE

137,325

DESIGN FOR A HAT DISPLAY STAND

Henry R. Portis, Chicago, Ill.

Application November 29, 1943, Serial No. 111,806

Term of patent 14 years

To all whom it may concern:

Be it known that I, Henry R. Portis, a citizen of the United States and resident of Chicago, in the county of Cook and State of Illinois, have invented a new, original, and ornamental Design for a Hat Display Stand, of which the following is a specification, reference being had to the accompanying drawing, forming a part thereof.

Fig. 1 is a view in perspective of a hat display stand embodying my new design.

Fig. 2 is a side elevational view of the article, on a reduced scale; and

Fig. 3 is a top plan view of the same.

I claim:

The ornamental design for a hat display stand, substantially as shown.

HENRY R. PORTIS.
